UNITED STATES PATENT OFFICE.

CHARLES G. RICHARDSON, OF BOSTON, MASSACHUSETTS.

LATHE.

SPECIFICATION forming part of Letters Patent No. 481,717, dated August 30, 1892.

Application filed January 25, 1892. Serial No. 419,156. (No model.)

To all whom it may concern:

Be it known that I, CHARLES G. RICHARDSON, of Boston, in the county of Suffolk and State of Massachusetts, have invented certain new and useful Improvements in Lathes, of which the following, taken in connection with the accompanying drawings, is a specification.

My invention relates to that class of lathes which are provided with a series of cutting-tools supported and carried by an intermittently-revolvable carrier, and which are usually termed "turret-lathes;" and it consists in certain novel features of construction, arrangement, and combination of parts, which will be readily understood by reference to the description of the drawings and to the claims hereinafter given and in which my invention is clearly pointed out.

Figure 1 of the drawings is a front elevation of a lathe illustrating my invention. Fig. 2 is a central, vertical, and longitudinal section through the head-stock and the parts of the bed in proximity thereto. Fig. 3 is a vertical transverse section on line 1 1 on Fig. 2, looking toward the left of said figure. Fig. 4 is a similar section on line 2 2 on Fig. 2, looking in the same direction. Fig. 5 is a transverse section through the bed on line 3 3 on Fig. 1 and showing the turret or tool-carrying ring and the head-stock in elevation. Fig. 6 is a transverse section on line 4 4 on Fig. 1 and showing the turret or tool-carrying ring in elevation. Fig. 7 is a sectional elevation of the central portion of the machine, the cutting-plane being on line 5 5 on Fig. 5. Fig. 8 is an elevation of a portion of the bed, the rack, and the gears for feeding the tool-carrier and its carriage toward and from the head-stock. Fig. 9 is a central, vertical, and longitudinal section of a portion of the bed and of the turret or tool-carrying ring and its carriage. Fig. 10 is a partial horizontal and longitudinal section of the bed and shows in plan the mechanism for revolving the tool-carrier and locking the same. Fig. 11 is an elevation of a short section of the hand-operated shipper-bar for operating the friction-clutch. Fig. 12 is an elevation of a portion of the shaft that carries the rest-bars for regulating the lengths of feed of the turret-carriage and the ratchet mechanism for

intermittently rotating the same. Fig. 13 is a partial transverse section on line 6 6 on Fig. 9. Fig. 14 is a partial section on line 7 7 on Fig. 13; and Fig. 15 is a sectional plan of the radius-arms, worm, and pinion of the carriage-feeding mechanism.

In the drawings, A is the bed of the machine, provided with the ways A' A' and supported at one end by the pier-like tool-closet B and at its other end by the leg B', the foot of which sets in the oil-receiving pan C, supported at one end by the closet B and at its other end by the leg C', as shown in Fig. 1.

The bed A has secured thereon at one end the head-stock D, which has mounted in suitable bearings therein the hollow spindle E, upon which is mounted so as to be freely revoluble thereon the cone-pulley F and the spur gear-wheel F', said gear F' having formed thereon the annular rib F², which fits within the larger end of the cone-pulley F and is held in position on said spindle by the collar G and the sleeve or hub G', both firmly secured to and revoluble with said spindle, and the latter has fitted thereon, so as to revolve therewith and be movable endwise thereof, the friction-wheel H. The friction-wheel H has formed upon its periphery two frusto-conical surfaces meeting each other at an angle in the center of said periphery, as shown, and said wheel also has formed in one side thereof, near its periphery, an annular groove, in which is fitted and held in place by the ring a the L-shaped ring b in such a manner that it may revolve in unison with the gear F' whether the wheel H revolves at the same or a different speed or is in a state of rest.

The ring a has formed thereon a series of alternate projections c and recesses c' to form one-half of a clutch, as shown in Fig. 3, which when desired engages with a similar clutch-ring d, firmly secured to the inner face of the web of the gear-wheel F', as shown in Fig. 2.

The friction-wheel H has formed upon its side opposite the ring a a set of clutch-teeth e, which engage when desired with similar clutch-teeth e' on the ring e², secured to the inner web-plate F² of the cone-pulley F, as shown in Fig. 2.

A ring f is fitted within the cone-pulley F, so as to revolve therewith and be freely movable in the direction of the length of said pul-

- ley to a limited distance, which is determined by the stop-pins f' , the inner periphery of said ring being provided with a beveled surface to fit one of the frusto-conical surfaces 5 of the wheel H and with the annular shoulder f^2 , which engages a similar shoulder on the wheel H, said ring being normally pressed toward the right of Fig. 2 by the springs $g\ g$, interposed between it and the web-plate F², said 10 web having formed therein recesses $g'\ g'$ to receive one end of each of said springs, as shown. A similar ring h is fitted within the annular rib F³ of the gear F', so as to revolve therewith and be freely movable therein in the direction of the length of the spindle E, said 15 movement being limited in both directions by the stop-pin h', and the inner periphery of said ring being beveled to fit one of the frusto-conical surfaces of the wheel H and also provided 20 with the annular shoulder h², against which the side of the wheel H abuts when moved into contact therewith, said ring h being normally pressed toward the wheel H by the springs h³, set in recesses in the web of the gear-wheel 25 F', as shown in Fig. 2.
- I is a shipper-ring fitted to and movable around and lengthwise of the collar G and having formed in its periphery the annular groove i to receive the blocks i' i', mounted 30 on studs set in the ends of the forked arm of the shipper-lever J, as shown in Figs. 2 and 4.
- The shipper-ring I is connected to the L-shaped ring b by a plurality of studs j, so that a movement of said shipper-ring in either 35 direction lengthwise of the spindle E will cause a corresponding movement of the friction-wheel H, causing it to engage with one or the other of the rings f or h and by the friction between their contiguous surfaces 40 cause the spindle to revolve in unison with the cone-pulley F or the gear-wheel F', according as to whether the shipper-ring is moved toward the left or right of Fig. 2. The first part of the movement of the shipper-ring 45 I and the friction-wheel H in either direction will cause frictional contact between said wheel H and one of the rings f h, and a further movement of said parts in the same direction will cause an engagement of the toothed clutch 50 on one side or the other of said wheel H, the ring f or h yielding to permit said further movement.
- The shipper J has an arm j', the movable end of which is fitted to and acted upon by 55 the cam-slot j², formed in the shipper-bar J', fitted to and movable endwise in a bearing in the head-stock D, as shown in Figs. 1, 2, 5, and 11.
- The cone-pulley F has firmly secured upon 60 its left-hand hub the spur-pinion K, which engages with the gear-wheel K', secured upon or formed in one piece with the sleeve K², mounted upon the shaft L, said sleeve having formed upon or secured to its opposite end the pinion K³, which engages with the gear F', all as shown in Figs. 2, 3, and 4.

The shaft L is mounted in bearings in the

head-stock D and has secured to its right-hand or inner end the frusto-conical collar or hub k, the purpose of which will be herein- 70 after described.

The bed A is composed of the sides A² A³, having the ways A' formed upon their upper edges, the central longitudinal bar A³, and a plurality of cross-ties A⁴, in addition to the 75 two end ties A⁵ and A⁶, as shown in Figs. 2, 9, and 10.

M is a carriage fitted to and movable endwise of the ways A', a portion of which surrounds the bed in the form of a ring or hoop 80 M', which encircles said bed and has fitted thereon, so as to be revoluble about said bed, the annular tool or work carrier N, having a polygonal periphery, all as shown in Figs. 6, 7, and 9. The tool or work carrier N has secured thereto or formed therein the internal gear l and is secured in place upon the ring M' of the carriage by the annular follower M², as shown in Fig. 9. The carrier N has a portion of its length at the end opposite the follower M² made circular and is provided at said end with the annular lip l', which encloses the flange of the ring M' and has formed in its inner surface the annular groove l², and said carrier also has formed in said end a series of cylindrical recesses m, corresponding in number to the number of flat surfaces upon the periphery of said carrier, each of said recesses having secured therein a hardened-steel bushing m', having a conical bore 95 or cavity, with which the frusto-conical end of the locking-bolt m², fitted to and movable endwise in a bushed bearing in the boss M³ on the upper side of the carriage M, engages, as shown in Fig. 9. The bolt m² has a slot 100 cut transversely through it and has formed in its inner end a cylindrical recess to receive the coiled spring n, which tends to hold said bolt normally in engagement with the bushing m', as shown in Fig. 9. 110

N' is a gear-wheel mounted on the stud n', set in the carriage M, the teeth of which engage with the teeth of the internal gear l and also with the teeth of the pinion N², mounted upon the shaft O, so as to be revoluble there- 115 with and movable endwise thereof, as shown in Fig. 9 and in dotted lines in Fig. 6.

The shaft O is mounted in bearings in the end of the bed and one of its cross-ties, so as to be movable endwise therein to a limited 120 extent and revoluble about its axis, and has secured to its left-hand end the coupling-hub O', which fits into and is firmly secured to the frictional sleeve O², the bore of which is made partly cylindrical and partly frusto-conical to 125 fit the frusto-conical hub or collar k, secured on the inner end of the shaft L, as shown in Fig. 10.

By the side of the shaft O and parallel with it is mounted in bearings in the same cross 130 connections of the bed, so as to be similarly movable endwise therein, the screw-shaft O³, provided on its outer end with the hand-wheel O⁴, by which it may be revolved, said shafts

O and O³ being connected together by the tie-block O⁵, through which both shafts pass, but are prevented from moving endwise therein by the collars o o and o' o', as shown in Fig. 10.

5 P is a block fitted to and movable freely endwise on the shaft O and having a threaded bearing on the screw-shaft O³, and P' is a hook-like pawl pivoted to the upper side of said block by the stud o² and provided at its 10 movable end with the upwardly-projecting wedge-shaped lug o³ and near the middle of its length with upwardly-projecting arm o⁴, said pawl being normally pressed into contact with the stop-pin o⁵ by the spring o⁶, as 15 shown in Figs. 9 and 10.

P² is a lever mounted on the fulcrum-pin p, set in the carriage M, and engaging at its upper end the slot in the locking-bolt m² and having its lower arm so arranged as to be 20 engaged by the lug o³ when the carriage is moved toward the right of Figs. 1, 7, 9, and 10, and thus retract the locking-bolt m² against the tension of the spring n.

The shaft O has fitted thereon between its 25 right-hand bearing and the collar o a coiled spring p', which serves to press the shafts O and O' toward the left of Fig. 10 when the downwardly-projecting portion M⁴ of the carriage is moved away from contact with said 30 block P, and thus release the contact of the conical surfaces of the hub k and the sleeve O².

The carriage is held down upon the ways A' and prevented from being lifted by means of the plates a' a', secured to the under side 35 of the upper plate of the carriage at its front and rear edges and projecting under the outwardly-projecting portions of the ways, as shown in Figs. 5, 6, and 7.

The front edge of the upper plate or the 40 main body of the carriage has firmly bolted thereto and pendent therefrom the outwardly-curved apron Q, to the inner side of which are bolted the pendent stands or hangers R, R', R², q, and q' and the inwardly-projecting bracket R³, as shown in Figs. 5 and 7. The plate Q also has formed thereon the outwardly-projecting hub Q', in which and the hanger q' the shaft S has its bearings, said shaft having firmly secured thereon the spur gear-wheel 45 S', the pinion S², and the hand-wheel S³, as shown in Fig. 5. The pinion S² engages with and imparts motion to the gear-wheel S⁴, which in turn engages with the teeth of the rack T, firmly secured to the front side of the 50 bed, as shown in Figs. 5, 6, 7, and 8. The shaft S has also mounted loosely thereon one end of each of two radius-arms S⁵ and S⁶, which extend horizontally toward the headstock and are connected together at their 55 movable ends and have mounted in suitable bearings therein a short shaft S⁷, upon which are mounted the worm-wheel S⁸ and the pinion S⁹, the teeth of said pinion engaging with and imparting motion to the gear-wheel S', and said worm-wheel S⁸ being rotated by the 60 worm S¹⁰, mounted upon a shaft having bearings in the hangers R and R' and having se-

cured thereon the gear-wheel S¹¹, which is acted upon by the pinion S¹², mounted upon the shaft S¹³, which is mounted in suitable 70 bearings in stands T' and T², secured to the bed A, and has secured on its left-hand end the cone-pulley T³, from which a belt (not shown) leads to the cone-pulley D', secured on the spindle E.

U is a shaft having bearings in the stands T² and T⁴ and having firmly secured thereto near its left-hand end the ratchet-wheel r, and also has loosely mounted thereon the two-armed lever r', having pivoted to one end 80 thereof the pawl r² to engage said ratchet and to its other end one end of the connecting-rod r³, the other end of which is connected to the upper or movable end of the lever U', firmly secured to one end of the rocker-shaft 85 U², mounted in suitable bearings on the bed A and having firmly secured thereon the two levers U³ and U⁴, the free ends of which are connected together by the bar or rod U⁵, as 90 shown in Figs. 3, 4, 6, and 10.

V is a lever pivoted to the follower-ring M², with its free end in position to bear against the bar U⁵, and V' V' are a series of cam-plates corresponding in number to the number of flat sides on the tool or work carrier N, 95 said cam-plates being secured to the end of said carrier next to the head-stock—one at each angle of said carrier—and so arranged relative to the lever V as to act thereon successively to vibrate said lever, and thus move 100 the bar U⁵ and the levers U', U³, and U⁴ about the axis of the rocker-shaft U² and through the rod r³, and lever r' cause the pawl r² to impart to the shaft U an intermittent movement about its axis.

The shaft U has firmly secured thereon one or more longitudinally-grooved hubs or cylinders W, in the grooves of which is adjustably fitted a series of bars s s, corresponding in number to the number of flat sides on the 110 tool-carrier, which bars may have smooth and straight outer edges, or they may have formed in said outer edges rectangular notches, as shown at the right hand end of Fig. 7. The rocker-shaft U², the levers V, U', U³, and U⁴, 115 and the pawl-carrying lever r' are returned to their normal positions after the passage of a cam-plate V' by the reaction of the spring V², (see Figs. 3 and 4,) and the outward movement of the lever V is limited by the stop-pin 120 s', the ratchet r being prevented from moving backward by the stop-pawl r⁴. The free or movable ends of the levers or radius-arms S⁵ S⁶ have pivoted thereto the lever or lifting-bar V³, having formed thereon the hook or 125 shoulder s² to engage one or another of the bars s s and provided at its upper end with the handle s³, by which the free ends of the levers S⁵ S⁶ may be raised to throw the worm-wheel S⁸ into engagement with the worm S¹⁰, 130 in which position said radius-arms and the worm-gear are held by the engagement of the shoulder s² with a bar s, as shown in Figs. 5, 6, and 7.

The spindle E carries at its inner end a chuck E', which may be of any usual or well-known construction, except that it must have a central opening through the same corresponding to the bore of said spindle, and said spindle is also provided near its outer end with a plurality of radially-arranged set-screws $t t$ to serve as a means of centering and guiding pipes or rods inserted through and clamped by the clutch and upon which the tools carried by the annular tool-carrier are to operate.

The shaft S¹³ has a spline-groove formed therein, which extends a greater part of the length of said shaft, by means of which and a suitable key the pinion S¹² is made to revolve therewith, while it is free to move endwise thereon when the carriage M is moved in either direction along the ways A'. The downwardly-projecting portion M⁴ of the carriage M is slotted to embrace the shaft O, as shown in Fig. 6, and is also slotted transversely of said shaft, so as to receive the pinion N² between two parts of said pendent lug and compel said pinion to move along said shaft O with the carriage M. The carriage M has set therein just above the front guide-way A' and at right angles thereto the push-pin u , the inner end of which is normally in a plane just outside the arm o^4 of the pawl-lever P', and its outer end projects into the annular groove l² in the inner surface of the annular ring l¹ of the tool or work carrier N, said push-pin u being surrounded by the coiled spring u' , which tends to force said pin outward, so that its outer end will project into the groove l² and into the path of the inner ends of the series of pins v, set in the cylindrical portion of the tool-carrier, one just outside of each angle of the polygonal portion of said carrier in positions parallel to the axis of rotation of said carrier, as shown in Figs. 6, 13, and 14.

The tool-carrier N may have secured thereon as many tool-holders and back-rests or work-supports as there are flat sides formed on its periphery, and said tool-holders may be of various forms.

I have illustrated one form of a box tool-holder and back-rest combined of novel construction, the same being shown secured to the annular tool or work carrier in Fig. 6 and drawn to an enlarged scale in Figs. 15, 16, 17, and 18, in which W' is the base-plate, provided with holes w w to receive the bolts for securing it to the tool or work carrier and having formed in its upper side the grooves w' and w², in the former of which is fitted so as to be adjustable therein the stand W², in which is mounted so as to be revoluble therein the shaft w³, having formed upon one end the slotted head W³ and having firmly secured upon its other end the worm-wheel W⁴, as shown in Figs. 16 and 17. The upper end of said stand W² projects outward over the worm-wheel W⁴ and is forked to form two bearings for the shaft of the worm W⁵,

upon one end of which shaft is secured the crank W⁶, by which said worm may be revolved to move the worm-wheel and the hub 70 or head W³ about its axis to adjust the angle of the cutting-tool X, adjustably secured in the slot of the head W³ by the set-screw w⁴, as shown. The stand W² is firmly secured in the proper adjusted position upon the base-plate W' by means of the bolt w⁵, passing through the slot w⁶ in said stand and screwed into the base-plate W', as shown. The groove w² is dovetailed and has fitted so as to be movable endwise therein the stand Y, having a central opening cut through it for the passage of the pipe, rod, or other piece of work to be operated upon, said stand being slotted vertically to receive the two levers Y' and Y², which together serve as a back-rest 85 to support the work. The short arms of these back-rest levers are connected together by the spring x, and their longer arms may be adjusted toward and from each other by the set-screws x' and x², as shown in Figs. 15 90 and 16. The front end of the stand Y is made L-shaped, and the inner portion of its base-flange has formed therein a series of rack-teeth, with which a series of teeth z, formed on a segment of the periphery of the head 95 W³, engage, so that when the head W³ is turned to advance and lower or retract and raise the point of the tool X the stand Y and the back-rest Y' Y² will be moved toward or from said tool simultaneously with said movements of the cutting-tool.

The operation of my invention is as follows: The work being passed through the hollow spindle E so as to project through the chuck E' the desired distance and adjusted to 105 a central position therein by the chuck E' and the set-screws $t t$ and the tool-carrier having secured on its periphery the proper tool-holders fitted with suitable tools for the job in hand, the carriage is moved toward the right of Fig. 1 110 to the proper position for beginning the work by turning the hand-wheel S³, the worm-wheel S⁸ being thrown out of engagement with the worm S¹⁰ by dropping the movable ends of the radius-arms S⁵ and S⁶ upon the bracket R³. 115 The screw-shaft O³ is then revolved by its hand-wheel O⁴ to bring the block P and the pawl-lever P' into the position relative to the lever P², (shown in Fig. 9,) the spring o⁶ yielding to allow the wedge-shaped lug o³ to pass 120 the lower end of the lever P² if said lever P² happened to be at the right of said lug before the screw O³ was operated to adjust said block P. One or more of the rest-bars s s, according as to whether there are one or more operations to be performed upon the piece of work in the chuck, are then adjusted longitudinally 125 in their carrying hubs or cylinders to the proper positions, so that one end of each bar or a notch therein shall be at a distance from the hook or shoulder s² on the lifting-bar V³ corresponding to the length of cut to be made by the tool to be controlled thereby. The worm-gear S³ is then raised into engagement 130

with the worm S^{10} by raising the radius-arms $S^5 S^6$, which may be done by lifting upon the handle s^3 at the upper end of the lifting-bar V^3 or upon the stud s^4 , set in the movable end of the radius-arm S^5 and projecting through a slot in the apron Q , (see Figs. 6 and 7,) when the hook or shoulder s^2 will engage with the bar s which is in proper position and adjusted to gage the first cut, and thus maintain the engagement of the worm-wheel S^8 and the worm S^{10} until the cut is completed, the upper end of the lifting-bar V^3 being normally pressed toward the bar s by the spring s^5 . (See Figs. 5 and 6.) The cutting-tools and back-rests being properly adjusted for the different cuts of the several operations and the several parts of the friction-clutch mechanism being in the positions shown in Fig. 2 and power being applied to the cone-pulley F , the hand shipper-bar J' is pushed inward or drawn outward, according as a fast or slow rotation of the work is required, the effect of which is to cause an engagement of one of the frusto-conical surfaces of the wheel H with a ring f or h with sufficient friction to cause said wheel H and the spindle E to commence to revolve, the springs g or h^3 yielding, so that the ring f or h may move lengthwise of the spindle after said frictional contact has taken place, so that the toothed clutch on one side or the other of the wheel H may be made to engage, the tension of the springs g and h^3 being so proportioned or adjusted as to permit sufficient slip of the frictional surfaces to insure such engagement of the toothed clutch if the two parts happened to be in positions relative to each other unfavorable to direct engagement without a partial rotation of one of the parts relative to the other. The work is thus revolved in unison with the spindle E , and the shaft S^{13} is rotated at the desired speed through the medium of the cone-pulleys D' and T^8 and a suitable belt connecting said pulleys, and the shaft L is also revolved by the action of the pinion K upon the gear-wheel K' . The rotation of the shaft S^{13} , acting through the pinion S^{12} , the gear S^{11} , the worm S^{10} , the worm-wheel S^8 , pinion S^9 , gear S' , pinion S^2 , gear S^4 , and the rack T , causes the carriage and the tool-carrier to be moved toward the head-stock D until the limit of the cut desired is reached, at which time the rear side of the shoulder s^2 on the lifting-bar V^3 reaches the left-hand end of the rest-bar s upon which it has been supported, or the rear side of a notch in said bar, and is released from support, and the movable ends of the radius-arms $S^5 S^6$ fall by the force of gravity, thus disengaging the worm-wheel S^8 from the worm S^{10} and the feed of the carriage is arrested. The operator then turns the hand-wheel S^3 about its axis in the proper direction to move the carriage toward the right-hand end of the bed A , or away from the head-stock, until the lower end of the lever P^2 comes in contact with the lug o^3 of the pawl P' , and said lever P^2 is moved about its fulcrum-pin, so as to retract the locking-bolt m^2 from engagement with the bushing M' , when the pendent lug M^4 of the carriage M comes into contact with the end of the block P and moves it and the shafts O and O^3 toward the right against the tension of the spring p' a sufficient distance to cause a frictional contact between the frusto-conical hub k and the sleeve O^2 of adequate force to cause said shaft O to revolve and through the medium of the pinion N^2 , the gear-wheel N' , and the internal gear l cause the tool-carrier to be moved about its bearing on the carriage until one of the pins v comes into contact with the outer end of the push pin u and moves it inward a sufficient distance to move the pawl P' around its pivot until the lug o^3 is removed from the path of the lever P^2 , at which time the operator releases the pressure on the wheel S^8 , when the reaction of the spring n will throw the bolt m^2 into engagement with the bushing m' and lock the tool-carrier N against further revolution, when the friction-surfaces of the hub k and sleeve O^2 will slip to prevent breakage of the parts. During the partial rotation of the tool-carrier, as above described, one of the cam-plates V' strikes the lever V and moves it about its pivot, thereby moving the bar U^3 and the levers U' , U^3 , and U^4 about the axis of the rocker-shaft in the direction indicated by the arrow on Figs. 3, 4, and 6 and through the rod r^3 and the lever r' causing the pawl r^2 to move the shaft U about its axis an angular distance equal to the distance between two of the bars $s s$, carried by said shaft, when the radius-arms $S^5 S^6$ are raised by the operator to throw the worm-wheel S^8 into engagement with the worm S^{10} and cause the shoulder s^2 on the lifting-bar V^3 to engage the bar s brought into position by the last partial rotation of the shaft U , when the carriage will again be fed forward toward the head-stock until said lifting-rod is disengaged, as before, from its supporting-bar s .

In certain cases when it is necessary to turn long rods or pipes that project a considerable distance beyond the chuck toward the right I reverse the operation of the machine—that is, I move the carriage by hand to the left in close proximity to the chuck and do the turning or cutting of the work while the carriage is being fed automatically toward the right, or away from the head-stock, the feeding of the carriage being arrested by the lifting-bar V^3 dropping from the right-hand end of the bar s or a notch therein, the operating-tools being properly constructed and adjusted to the changed conditions.

The advantages of my invention are that the tool-carrier may be increased in size, and consequently in capacity for holding a larger number of tools, without occupying any more space on the top of the lathe-bed or raising its uppermost side any higher. Only one tool-holder is uppermost at the same time and that the one that is operating upon the work. The

tool-carrier is rotated automatically, and the limit of the cut is automatically determined in all cases, whether the cut is made by feeding the carriage toward or from the chuck.

5. What I claim as new, and desire to secure by Letters Patent of the United States, is—

1. In a lathe, the combination of a work holding and rotating chuck, a bed provided with suitable ways, a carriage supported by 10 and movable endwise of said ways, and an annular tool-carrier surrounding said bed and supported by said carriage and having provision for securing the cutting-tool holders to it.

15. 2. The combination, in a lathe, of a bed having suitable ways, a work holding and rotating chuck carried by said bed, a carriage mounted upon and movable along said ways and provided with a ring-like portion extending 20 around said bed, and an annular carrier fitted to said ring-like portion of said carriage and surrounding said bed, mechanism for automatically moving said carrier about said bed and carriage, and means having provision 25 for locking said carrier after each intermittent partial rotation.

3. The combination, in a lathe, of a bed having suitable ways, a work holding and rotating chuck supported by said bed, a carriage 30 mounted upon and movable endwise of said ways, a tool-carrier mounted on said carriage and revoluble thereon, a toothed rack secured in a fixed position on said bed, a worm carried by said carriage, a worm-wheel and a 35 train of gears interposed between said rack and worm, said worm-wheel and certain of the gears being carried by pivoted radius-arms, a revolving shaft driven or operated from any suitable source of power, suitable gears for 40 imparting motion from said shaft to the worm, an intermittently-revolving shaft, a ratchet-and-pawl mechanism connected with said shaft, a series of cams on the tool-carrier for operating said ratchet-and-pawl mechanism, 45 a series of rest-bars arranged around, carried by, and adjustable lengthwise of said shaft and a lifting-bar for raising said worm-wheel into contact with the worm and constructed and arranged to maintain such contact by engagement 50 with one of said rest-bars, whereby the length of feed of the carriage and tool-carrier is determined by the distance from said lifting-bar at the start to the end of said bar or a notch therein where said lifting-bar 55 is disengaged.

4. The combination, in a lathe, of a bed having suitable ways, a work holding and rotating chuck, a carriage mounted upon and movable endwise of said ways and surrounding 60 said bed, an annular tool-carrier mounted upon said carriage and surrounding it and said bed and having a polygonal outer periphery fitted to receive a tool-holder on each of the flat sides of the polygon, a bolt for locking 65 said carrier, a series of sockets in said carrier to receive said bolt, a constantly-revolving shaft operated from any suitable source

of power, a second shaft, a friction-clutch mechanism interposed between said shafts and adapted to connect them and cause said 70 second shaft to revolve, a pinion on said second shaft revoluble therewith and freely movable endwise thereof, an internal gear mounted on said carrier and adapted to be revolved about its axis by the revolution of said pinion, a lug pendent from the upper portion of the carriage and slotted to embrace or straddle said shaft and pinion and adapted to engage and move the pawl-carrying block, an adjustable block, a pawl pivoted to said block 80 and provided with an upwardly-projecting wedge-shaped lug, a two-armed lever pivoted to the carriage and engaging the locking-bolt by one of its ends and having its opposite end in position to engage said wedge-shaped 85 lug, means having provision for adjusting the pawl-carrying block on its shaft and means having provision for holding said block in position on its shaft without interfering with the rotation of said shaft, and a spring 90 constructed and arranged to permit a slight endwise movement of said pinion-carrying shaft.

5. The combination, in a lathe, of the bed A, provided with ways A' A', a work holding 95 and rotating chuck, the carriage M, the carrier N, a constantly-revolving shaft operated from any suitable source of power and provided with the friction-clutch hub k, the shaft O, provided with a longitudinal spline-groove 100 and the female coupling-sleeve O², the pinion N², the spur-gear N', the internal gear l, mounted on the carrier, the block P, movable endwise on the shaft O, the pawl P', provided with the wedge-shaped lug o³ and the arm o⁴, 105 the spring o⁶, the screw-shaft O³, fitted to a threaded hole in the block P, the tie-block O⁵, connecting said shafts, as set forth, the spring p', the lever P², the locking-bolt m², the spring n, a series of bushings m', set in the carrier, 110 the push-pin u, mounted in the carriage, as set forth, the spring u', and the series of pins v, set in the carrier and adapted to act upon said push-pin to move it endwise to trip the pawl P' from engagement with the lever P² 115 to allow the locking-bolt to engage with said bushings.

6. In a lathe head-stock, the combination of a chuck-carrying spindle, a cone-pulley mounted loosely thereon and carrying a spur-gear, a gear-wheel also mounted loosely on said spindle between two collars or sleeves firmly secured to said spindle, suitable gears connecting the gear on the cone with the gear on the spindle, a friction-wheel mounted upon 125 said spindle, so as to be revoluble therewith, and movable endwise thereof and having its outer periphery composed of two frusto-conical surfaces, two friction-rings fitted one within the cone-pulley and the other within 130 the rim of the gear loosely mounted on the spindle, said rings having their inner surfaces shaped to fit the frusto-conical surfaces of said friction-wheel and being connected

to said cone and gear, so as to be revoluble therewith and movable therein toward or from each other, springs for moving said rings toward each other, a toothed clutch on each 5 side of said friction-wheel, and a shipper mechanism constructed and arranged to move said friction-wheel lengthwise of said spindle in either direction and cause it to first engage one of the friction-rings and then one 10 of the positive clutches.

7. In a lathe, the combination, with the bed and a carriage mounted on and movable endwise of said bed, of a tool-carrier mounted on 15 said carriage and intermittently revoluble thereon, a constantly-revolving feed-shaft, a train of feed-gearing constructed and arranged to be thrown into and out of connection with said feed-shaft, an intermittently-revoluble shaft, a series of rest-bars arranged 20 around and parallel to said shaft and adjustable lengthwise thereof, and a lifting-bar for raising the train of feed-gearing and provided with a shoulder to engage said rest-bars, substantially as described.

25 8. The combination, in a lathe, of a bed having suitable ways, a work holding and rotating chuck supported above said bed, a carriage mounted upon and movable endwise of said ways, a tool-carrier mounted upon said 30 carriage and revoluble thereon, a rest-bar supported by and adjustable lengthwise of said bed, a bar or lever mounted upon and movable with said carriage and constructed and arranged to bear upon said rest-bar during the movement of said carriage and adapted 35

to drop off the end of said rest-bar or through a notch cut therein, and mechanism interposed between said bar or lever and said carriage whereby the movement of said carriage will be stopped by the disengagement of said 40 bar or lever from said rest-bar.

9. The combination, in a lathe, of a bed having suitable ways, a work holding and rotating chuck supported above said bed, a carriage mounted upon and movable endwise of 45 said ways, a tool-carrier mounted upon said carriage and revoluble thereon, a series of rest-bars supported by and independently adjustable endwise of said bed, mechanism for throwing either of said rest-bars into position 50 for action, a bar or lever mounted upon and movable with said carriage and constructed and arranged to engage with or bear upon the rest-bar in action during the movement of said carriage and adapted to drop off the end 55 of said bar or through a notch cut therein, and mechanism interposed between said bar or lever and carriage whereby the movement of said carriage will be stopped by the disengagement of said bar or lever from said rest- 60 bar.

In testimony whereof I have signed my name to this specification, in the presence of two subscribing witnesses, on this 13th day of January, A. D. 1892.

CHARLES G. RICHARDSON.
